HINGE

Adolf Ensslin, North Attleboro, Mass.

Application October 13, 1936, Serial No. 105,396

10 Claims. (Cl. 16—153)

My invention relates to hinges for house doors, gates, and other swingable elements, and has particular utility for use in connection with doors of unusual weight, including those employed in 5 refrigerators and safes wherein a maximum of strength and smoothness of operation is imperative, but these uses are not exclusive.

Heretofore it has been attempted to construct 10 hinges by interengaging two helically wound un-twisted strips, with the result that the coils or helices of one member of the hinge engaged the coils of the other member edgewise, thus affording a bearing surface limited in area to the thickness of the material of the coils, which resulted in inadequate stability of the hinge when 15 employed upon doors of substantial weight. When it was attempted to cure this defect by increasing the thickness of the material of the coils it was found impractical to mechanically wind the material, and when recourse was had to casting the material of the coils, the weight 20 of the hinge members was excessive, and the coils under strain were subject to the fractures characteristic of all cast metals.

The essential objects of my invention are stability, extensiveness of bearing areas, amplitude 25 of space available for lubrication, smoothness of motion, and relative lightness of weight.

Further objects are to render unnecessary both 30 axial cores or trunnions and door springs.

Other objects and advantages of this invention will be hereinafter adverted to.

To the above recited and indicated ends primarily the present invention consists in such 35 parts and combinations of parts as fall within the scope of the appended claims.

In the accompanying drawing which forms a part of this specification,

Figure 1 is a front elevation of a door and the 40 adjacent portion of a structure in which the door is mounted showing hinges of the present invention applied thereto,

Figure 2, an enlarged fragmentary front elevation of said structure and door including one of 45 the hinges, the door being closed,

Figure 3, a similar elevation of the same, the door being open,

Figure 4, a fragmentary plan view of one of the hinges,

Figure 5, a horizontal transverse section on line 50 5—5 of Figure 2, and

Figure 6, a diagonal transverse section taken on line 6—6 of Figure 3.

Similar characters of reference indicate similar 55 parts throughout the views.

In the drawing 10 represents a structure provided with a door opening 11, and a door 12 herein shown as supported in the opening by hinges 13, both of like construction. The number of hinges may be one or more. In this instance a 5 blind clearance, as at 14, is afforded by a bevel, inclined transversely and longitudinally in the top edge of the door.

Each hinge 13 is composed of two interengaging hinge elements 17 and 18. Element 17 comprises upper and lower terminal leaves 20 including laterally extending vertically disposed attaching portions 21, and forwardly directed plane flange portions 22 integral with the top and bottom edges of the upper and lower attaching portions 15 respectively. An intermediate strip 23 is integral at its ends with the adjacent lateral edges 24 of the flange portions 22 of the leaves.

The strip 23 which is of generally spiral form is twisted so that, as shown in Figure 6, the strip 20 with its constituent twists 25, is in diagonal transverse section, concavo convex, comprising lengthwise of the strip, a curved central or body portion 26 and curved lateral flange portions 27. The axial line 28 of the hinge element or strip 25 23, as twisted, in this instance, coincides with the bearing face of the body portion 26 of the twisted strip axially thereof.

The hinge element 18 is identical in construction with the element 17, but oppositely disposed. 30 It comprises terminal leaves 30, including attaching portions 31 and flange portions 32. Integral with the latter is an intermediate strip 33 35 integral with the lateral edges 34 of the flange portions 32.

The strip 33 is so twisted as to be complementary with the strip 23, and has constituent twists 35 engaging the twists 25, and, in diagonal transverse section, the strip is concavo convex comprising body portion 36 and curved flange portions 37, 40 slidably registering respectively with the similar portions 26 and 27 of the strip 23. The interengaged strips constitute the body of the hinge.

The leaves 20 and 30 are attached to the door 45 and structure respectively by attaching screws 40 passing through perforations 42 in the attaching portions of the wings.

In moving the door 12 the interengaged helical strips have both a rotary movement and a slightly vertical movement, so that in opening the door escapes any obstruction in front of the lower portion thereof, and the weight of the door serves to automatically return it to its original closed 50 position.

It will be observed that the edges of the inter-engaging twists have no bearing contact with each other. Instead, the diagonally transversely curved faces of the body portions and of the flange portions of the adjacent spiral strips 23 and 32 have nonedgewise contact with each other.

5 The avoidance of edgewise contact of the twists permits the employment of easily twisted thin material in the hinge elements without danger 10 of collapse, particularly in heavy doors.

15 The diagonally transversely curved construction described furnishes increased contacting bearing areas of the interengaging strips relatively to their width thus increasing the strength and stability of the structure.

19 The increased extent of the bearing areas of the strips affords maximum areas for the distribution of lubricant upon their contacting surfaces.

20 In the diagonally transversely curved construction of the strips above described the curved flanges contribute to the intimacy of their interengagement and tend to resist strains transversely of the hinge.

25 The flanges 22 and 32 maintain the interengaging strips in a vertical position whereby the body of the hinge is not subjected to any lateral strains, and the twists of the body are enabled to extend to the extremities of the constituent strips of the body.

I claim:

30 1. In a hinge, a plurality of spirally twisted and interengaged strips providing face bearing contact with each other.

35 2. In a hinge, a plurality of strips spirally twisted longitudinally with the twists interengaged to provide face-to-face bearing contact with each other, and terminal leaves upon the strips.

40 3. In a hinge, a plurality of strips spirally twisted and interengaged with face bearing contact with each other, and attaching leaves carried by the strips.

4. In a hinge, thin twisted complementary bearing strips of diagonally arcuate form having their peripheral edge faces exposed, and attaching means supported by the ends of the strips.

5. In a hinge, a body comprising two strips spirally twisted longitudinally with the twists interengaged with each other and in slideable contact with each other throughout their lengths, and attaching means carried by the ends of the strips.

10 6. In a hinge, two thin complementary inter-engaging twisted strips concavo convex in diagonal section comprising bearing faces interengaged throughout their areas and edges out of contact throughout their lengths, and terminal 15 attaching means carried by the strips.

7. In a hinge, a body comprising two interengaging spirally twisted strips, each of the strips being nested in the other strip in face bearing contact therewith, and terminal attaching means 20 carried by the strips.

25 8. In a hinge, two complementary interengaging twisted strips comprising central longitudinally disposed body portions, and lateral transversely inclined flange portions, the body portion and flange portions of one strip having bearing contact with the entire areas of the body portion and flange portions of the other strip, and terminal attaching means carried by the strips.

30 9. In a hinge, two interengaging spirally twisted strips, and leaves comprising attaching portions and flange portions, said flange portions being disposed at right angles to the attaching portions and integral with the ends of the strips.

35 10. In a hinge, two spirally twisted strips interengaged throughout their lengths, and leaves comprising attaching portions disposed in a vertical plane, and flange portions disposed in horizontal planes, said flange portions being laterally 40 integral with the ends of the strips.

ADOLF ENSSLIN.
